DESIGN FOR A GENERATOR HOUSING SIDE
PLATE FOR GASOLINE ENGINES

Floyd A. Sherman, Cleveland, Ohio

Application May 19, 1948, Serial No. 146,446

Term of patent 3½ years

(Cl. D26—5)

To all whom it may concern:

Be it known that I, Floyd A. Sherman, a citizen of the United States, residing at Cleveland, county of Cuyahoga, and State of Ohio, have invented a new, original, and ornamental Design for Generator Housing Side Plate for Gasoline Engines, of which the following is a specification, reference being had to the accompanying drawing, forming a part thereof.

Fig. 1 is a front elevational view of a generator housing side plate embodying my new design;

Fig. 2 is a top plan view of the side plate;

Fig. 3 is a rear elevational view of the side plate, and

Fig. 4 is a vertical cross-sectional view of the side plate, taken on the line 4—4 of Fig. 1.

I claim:

The ornamental design for a generator housing side plate for gasoline engines, substantially as shown.

FLOYD A. SHERMAN.
